UNITED STATES PATENT OFFICE.

KIMMEL DARR AND HARVEY S. GLUNT, OF EL DORADO, PENNSYLVANIA.

BRICKLAYER'S HAMMER.

Application filed February 12, 1925. Serial No. 8,715.

This invention relates to improvements in hammers and more particularly to the type used by bricklayers and masons.

One of the important objects of the present invention is to provide a bricklayer's hammer wherein the same is provided with means for facilitating the extraction of nails, thus obviating the necessity of having to carry an extra hammer or nail extractor for such purposes.

A still further object is to provide a bricklayer's hammer of the above mentioned character, which is simple in construction, strong and durable and further well adapted for the purposes for which it is designated.

Other objects and advantages of this invention will become apparent during the course of the following description.

In the accompanying drawing forming a part of this specification wherein like numerals designate like parts throughout the same:

Figure 1 is a side elevation of the improved hammer.

Figure 2 is a bottom plan view of the hammer head, and

Figure 3 is a sectional view taken approximately on line 3—3 of Figure 1.

In the drawing wherein for the purpose of illustration is shown the preferred embodiment of our invention, the numeral 1 designates generally the head of a bricklayer's hammer, the same being provided at one end with the usual driving head 2 and at its opposite end with the usual blade 3. As the use of the hammer is well known in the art and as the same forms no important part of the present invention, a further detailed description thereof is not thought necessary. The central thickened portion 4 of the hammer head is provided with the usual socket 5 for receiving the upper end of the handle 6.

A pair of substantially rectangular shaped sockets 7 and 8 respectively are formed in the inward face of the driving head 2 adjacent the respective sides thereof and in the intermediate portion of the same as clearly illustrated in Figures 2 and 3. Cooperating therewith are the inwardly enlarging notches 9 and 10 respectively, the same being formed in the sides of the driving head 2. This

construction provides a means whereby the nail which is to be extracted has its head disposed in either of the sockets and the adjacent portion of the shank of the nail being disposed within the respective notches. Thus a nail may be readily and easily extracted by using the driving head 2 of the bricklayer's hammer and there will be no possibility of the same becoming disengaged from the nail during the extraction of the latter.

Depending from the sides of the blade portion 3 of the hammer head 1 and formed integrally with the adjacent side of the central portion 4 are the flanges or ears 11 and 12. The outer sides of these flanges or ears terminate at a point adjacent the intermediate portion of the blade. Each of these flanges or ears is provided with a tapering notch 13 in the bottom thereof as clearly illustrated in Figures 1 and 2.

The provision of the depending flanges or ears enables the blade portion of the hammer head to be used in extracting nails, the head of the nail to be extracted being held in engagement with the inner side or face of the flange or ear which is in use, the shank portion of the nail being disposed within the inwardly enlarging notch 13.

The provision of a bricklayer's hammer of the above mentioned character, wherein the same is provided with a nail extracting means enables a bricklayer or mason to use a single implement for a two fold purpose, namely, as a bricklaying tool and as a means for removing nails from scaffolding or the like thus obviating the necessity of a bricklayer having to carry an ordinary claw hammer or the like for the purpose solely of removing nails when disassembling a scaffold.

While we have shown the preferred embodiment of our invention, it is to be understood that various changes in the size, shape and arrangement of parts may be resorted to, without departing from the spirit of the invention and the scope of the appended claim.

Having thus described the invention, what we claim is:—

In a hammer head for a bricklayer's hammer wherein the same includes the usual

driving head portion, the latter being provided with a socket in the inward face of the intermediate portion thereof adjacent to the side of the same, said driving head being further provided with an inwardly enlarging notch in said side communicating with said socket, the shank portion of a nail to be

extracted being disposed in said notch, the head portion of said nail being disposed in said socket. 10

In testimony whereof we affix our signatures.

KIMMEL DARR,
HARVEY S. GLUNT.
